UNITED STATES PATENT OFFICE.

JOHN ANDERSON ROBISON AND HENRY EARL LITTLEJOHN, OF GREER, SOUTH CAROLINA.

LOOM ATTACHMENT.

1,272,532.

Specification of Letters Patent. Patented July 16, 1918.

Application filed February 19, 1917. Serial No. 149,557.

To all whom it may concern:

Be it known that we, JOHN ANDERSON ROBISON and HENRY EARL LITTLEJOHN, citizens of the United States, residing at 5 Greer, in the county of Greenville and State of South Carolina, have invented a new and useful Loom Attachment, of which the following is a specification.

The object of our invention is to provide 10 a novel double deck reed that will carry two shuttles at the same time, going in opposite directions, for weaving tubing and double-width cloths on single-width looms; and to provide a continuous box motion on each 15 side, to enable the loom to weave twice as much cloth per minute as is done by the old and present usual mode of weaving.

We attain the objects of our invention by 20 the mechanism illustrated in the accompanying drawings, in which—

Figure 1 is a side elevation of our invention applied to a loom; Fig. 2 is a diagrammatic illustration of the loom in operation; reed 3 having a projecting comb 4, as shown 25 device; Fig. 4 is a detail view of the cam mechanism; and Fig. 5 is an edge view of the double-reed device, on line 5—5 of Fig. 3.

Like characters of reference designate like 30 parts throughout the several views.

Referring to the accompanying drawings, 1 designates the frame, to which is mounted race 2. We provide a novel double-decked reed 3 having a projecting comb 4, as shown 35 in Figs. 3 and 5. To support a rocking lever 6, we provide a suitable strap 5 to which it is pivotally attached as shown in Fig. 1. Comb teeth 4 which project through reed 3 are frictionally engaged therewith and 40 the ends of the comb member 4 are soldered together to hold it permanently in place in the reed 3. To the ends of rocking lever 6 are attached brackets 7 which support boxes 8. We provide suitable shuttle levers 45 9 attached to the machine in any suitable manner. Mounted to the frame is a shaft 10, carrying cams 11. Referring to the enlarged view of the cams shown in Fig. 4, it will be observed that we provide opposite 50 enlarged portions 13, and opposite reduced portions 11, adapted to control and regulate the operation of the machine. Suspended from rocking lever 6 at either end are rods or levers 15, guided by brackets 14. Suit- able treadles 18 are provided at the lower 55 end of members 15 as shown in Fig. 4. We provide a suitable roller 17 mounted in member 15, and riding on the peripheral portion of cam 11 as shown in Fig. 4. Referring to Fig. 2, we provide double-eyed heddles 60 19, and shuttles 20. Referring to Fig. 5, 22 designates mountings for the reed 3, and 21 designates a mounting for the projecting comb 4.

In operating the device the treadles 18 on 65 levers 15 cause rocking lever 6 to tilt up and down thus raising and lowering boxes 8 alternately, while the shuttles are moving across the reed or comb from the box on one side to that on the opposite side of the 70 loom. While the shuttles are passing each other in the central portion of the machine the shuttle boxes are automatically changing their position from bottom to top and top to bottom to be in position to catch the shuttle 75 on its arrival. The left hand box rides to the top and catches the shuttle from the right, while the right hand box falls to the bottom and catches the shuttle coming from the left. Then the left hand box will lower its 80 shuttle to the bottom, and the right hand box will raise its shuttle to the top. The loom is then ready to pick from both ends (a double-pointed pick cam being used to cause the loom to pick from both ends at 85 the same time). Thus the shuttles are caused to make a complete loop. When the lay is on front center the extra race plate will be in the passage between the two layers of cloth inside the temples. Cloth will 90 weave together on each selvage. This will increase the production practically 100 per cent. With this attachment it is possible to weave tubular fabric and bag goods with 95 two shuttles, one going from left to right on the regular race plate, and the other going from right to left on the extra race plate.

What we claim is:

As a new article of manufacture, a double-decked reed having like mountings, having 100 a projecting comb and a mounting to which the shanks of the projecting comb elements are fastened, the comb projecting through and at right angles to the reed, and having its end permanently soldered to the reed. 105

JOHN ANDERSON ROBISON.
HENRY EARL LITTLEJOHN.
